WALL PAPER SCRAPER

Filed Oct. 15, 1932

Inventor:
Magnus Willadsen

By *J. Jochum*

UNITED STATES PATENT OFFICE

MAGNUS WILLADSEN, OF CHICAGO, ILLINOIS

WALL-PAPER SCRAPER

Application filed October 15, 1932. Serial No. 637,884.

This invention relates to improvements in wall paper scraper, and one of the objects of the same is to provide an improved hand tool by means of the use of which several thicknesses or layers of wall paper may be readily and expeditiously removed or scraped from a wall without injury to the wall.

A further object is to provide an improved device of this character in the form of a knife provided with a number of flexible prongs or tines, each of which is provided with a sharpened extremity to facilitate insertion or passage beneath the layers of wall paper.

5 A further object is to provide an improved tool of this character adapted to be inserted or passed under the layer of wall paper, and which tool is provided with upstanding cutting edges for severing the paper, thereby facilitating the operation of the tool.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which

30 Figure 1 is an elevation of a tool of this character constructed in accordance with the principles of this invention.

Figure 2 is an end elevation of Figure 1.

Figure 3 is a detail sectional view taken on line 3—3, Figure 1.

Figure 4 is a plan view of a portion of a modified form of blade.

Figure 5 is a view similar to Figure 4, with a portion of the blade deflected to form a cutting edge.

Figure 6 is an end elevation of Figure 5.

The tool consists essentially of a blade 10 formed of any desired or suitable flexible material and has preferably formed integral therewith a projecting portion 11 to which a handle 12 is secured. The handle may be of any desired size and length and constructed in any suitable manner, and the blade 10 is preferably tapered in thickness and is of a substantial length and width.

The blade is shaped to form a plurality of laterally spaced prongs or tines which are of substantial length so as not to interfere with their flexibility and are preferably substantially flat, the sides of the free extremities being preferably tapered as at 14 and sharpened to form cutting edges.

A portion 15 of the blank from which the blade is formed normally projects laterally beyond the side edges of the blade and this portion 15 is deflected so as to be disposed perpendicularly with and project beyond the face of the blade. The upper edge of the portion 15 when thus deflected inclines downwardly from a point adjacent the inner ends of the prongs or tines 13 towards but terminates considerably short of the free extremity of the tines as at 16. The edges 16 are shaped to form a cutting edge so that when the tool is employed and the extremities 14 of the tines 13 pass between the wall paper and the wall, the paper will be severed so as to permit of its ready and easy removal from the wall.

At the same time and owing to the flexibility of the tines 13, the surface of the wall will not be injured. Furthermore, by providing a series of separate cutting edges along the front extremity of the blade 10, preferably in the form of tines, the blade will more readily pass beneath the paper and less exertion will be required, but a more rapid operation of the device will result.

If desired and in order to protect the hand of the operator, a cushioning device 19 formed of any suitable material, but preferably rubber, may be arranged at the end of the handle 12.

In the form of the invention shown in Figures 4 to 6, the cutting edges are formed by cutting out a portion 17 of the blade 10 and then deflecting the cut out portion laterally so that the same will be disposed perpendicular to the face of the blade while the edge 18 will form an inclined cutting edge for severing the paper.

Obviously, any number of tines may be provided and these tines may be of any suitable length.

While the preferred forms of the invention

have been herein shown and described, it is to be understood that various changes may be made in the details of construction and in the combination and arrangement of the several parts, within the scope of the claims, without departing from the spirit of this invention.

What is claimed as new is:—

1. A hand wall paper scraper embodying a blade, said blade being of substantial length and width, said blade comprising a plurality of spaced elongated flexible prongs or tines, the sides of the free extremities of which tines converge to form a point. 10
- 15 2. A hand wall paper scraper embodying a blade, said blade being of substantial length and width, said blade comprising a plurality of spaced elongated flexible prongs or tines comparatively narrow with respect to their length, the sides of the free extremities of the tines converging to form a point and being shaped to form laterally faced cutting edges. 20
- 25 3. A hand wall paper scraper embodying a handle, a flexible blade to which the handle is connected, said blade decreasing in thickness to the free extremity thereof and being of substantial width and length, the blade being shaped to form a plurality of laterally spaced and substantially parallel tines of substantial length, sides of the free ends of the tines converging to the extremities thereof, and the lateral faces of such converging portions being shaped to form cutting edges. 30
- 35 4. A hand wall paper scraper embodying a blade, said blade comprising a plurality of spaced elongated prongs or tines, the free extremities of which tines are pointed, and a cutting edge projecting above the upper surface of the blade and extending in a general direction lengthwise thereof. 40
- 45 5. A hand wall paper scraper embodying a blade, a handle at one end thereof, said blade comprising a plurality of spaced elongated prongs or tines, the free extremities of which tines are pointed, and a cutting edge projecting above the upper surface of the blade and extending in a general direction lengthwise thereof, said cutting edge inclining down- 50 wardly from a point in proximity to the handle towards the free extremity of the blade. 60
- 55 6. A hand wall paper scraper embodying a blade, a handle at one end thereof, said blade comprising a plurality of spaced elongated prongs or tines, the free extremities of which tines are pointed, and a cutting edge formed integral with and projecting above the upper surface of the blade, said cutting edge ex- 65

tending in a general direction lengthwise of the blade and inclining downwardly from a point in proximity to the handle towards the free extremity of the blade.

7. A hand wall paper scraping tool embodying a flexible blade, and one or more cutting edges arranged perpendicular to and projecting beyond the face of the blade, said edges extending in a general direction lengthwise of the blade. 70

8. A hand wall paper scraping tool embodying a flexible blade, and one or more cutting edges arranged perpendicular to and projecting beyond the face of the blade, said cutting edge extending in a general direction lengthwise of the blade and being formed by a deflected portion of the blade. 80

9. A hand wall paper scraping tool embodying a flexible blade having a free end, and one or more cutting edges arranged perpendicular to and projecting beyond the face of the blade, said cutting edge being formed by a deflected portion of the blade and inclining upwardly from a point remote from but in proximity to the free end of the blade towards the other end thereof. 85 90

10. A hand wall paper scraping tool embodying a blade formed from a single piece of material shaped to form spaced and extended tines comparatively narrow with respect to their length, the free extremities of which are shaped to form cutting edges, a portion of the material being deflected to project beyond one face of the blade and shaped to form a cutting edge extending in a general direction lengthwise of the blade. 95

11. A hand wall paper scraping tool embodying a blade formed from a single piece of material shaped to form spaced and extended tines comparatively narrow with respect to their length, the free extremities of which are shaped to form cutting edges, a portion of the material being deflected to project beyond one face of the blade and shaped to form a cutting edge, inclining upwardly from a point in proximity to the free end of the tines towards the opposite end of the blade. 105 110

12. A hand wall paper scraper embodying a flexible blade, the forward edge of the blade being formed by a plurality of laterally spaced tooth like substantially flat portions, the sides of the ends of which are tapered to the extremities thereof, said tapered portions of said sides being shaped to form cutting edges. 115 120

MAGNUS WILLADSEN.
